(57) **CLAIM**

The ornamental design for an LED bulb, as shown and described.

DESCRIPTION

FIG. 1 is a perspective view of an LED bulb design showing my new design.

FIG. 2 is a front view of an LED bulb.

FIG. 3 is a rear view of an LED bulb.

FIG. 4 is a left side view of an LED bulb.

FIG. 5 is a right side view of an LED bulb.

FIG. 6 is a top view of an LED bulb; and,

FIG. 7 is a bottom view of an LED bulb.

Any shading and cross-hatching are not features of the design but are utilized to illustrate the surface contours of the LED bulb design in the drawings.

The broken lines illustrate portions of the LED bulb that form no part of the claimed design.
